(57) CLAIM

The ornamental design for a massage chair, as shown and described.

DESCRIPTION

FIG. 1 is a perspective view of the design according to the invention.

FIG. 2 is another perspective view of the design according to the invention.

FIG. 3 is a front view of the design according to the invention.

FIG. 4 is a back view of the design according to the invention.

FIG. 5 is a top view of the design according to the invention.

FIG. 6 is a right side view of the design according to the invention; and,

FIG. 7 is a left side view of the design according to the invention.

The bottom of the design is flat and unornamented and, therefore, a bottom view of the design is disclaimed.

The broken lines depict unclaimed portions of the massage chair and form no part of the claimed design.
